US00D784843S

(12) **United States Design Patent** (10) **Patent No.:** **US D784,843 S**
(45) **Date of Patent:** **** Apr. 25, 2017**

(54) **BRACELET**

(71) Applicant: **Alex and Ani, LLC**, Cranston, RI (US)

(72) Inventor: **Carolyn A. Rafaelian**, Cranston, RI (US)

(73) Assignee: **Alex and Ani, LLC**, Cranston, RI (US)

(**) Term: **15 Years**

(21) Appl. No.: **29/557,583**

(22) Filed: **Mar. 10, 2016**

(51) **LOC (10) Cl.** **11-01**

(52) **U.S. Cl.**

USPC **D11/5**

(57) **CLAIM**

The ornamental design for a bracelet, as shown and described.

DESCRIPTION

FIG. 1 is a top, front, left side, perspective view of a bracelet showing a first embodiment of our new design;

FIG. 2 is a top, front, right side, perspective view thereof;

FIG. 3 is a top plan view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a bottom plan view thereof;

FIG. 9 is a top, front, left side, perspective view showing a second embodiment thereof;

FIG. 10 is a top, front, right side, perspective view of FIG. 9;

FIG. 11 is a top plan view of FIG. 9;

FIG. 12 is a front elevation view of FIG. 9;

FIG. 13 is a rear elevation view of FIG. 9;

FIG. 14 is a left side elevation view of FIG. 9;

FIG. 15 is a right side elevation view of FIG. 9; and,

FIG. 16 is a bottom plan view of FIG. 9.
